UNITED STATES PATENT OFFICE.

DANIEL PYZEL, OF OAKLAND, CALIFORNIA, ASSIGNOR TO SIMPLEX REFINING COMPANY, OF SAN FRANCISCO, CALIFORNIA, A CORPORATION OF CALIFORNIA.

PROCESS OF UTILIZING CARBONACEOUS MATERIAL.

Application filed August 25, 1920. Serial No. 406,012.

My invention relates to the art of utilizing heavy carbonaceous material such as oil sands, oil shales, asphalt, heavy residuum from refining operations and heavy petroleum oils. It is particularly adapted to the utilization of asphalt, and the following description will be directed to the treatment of asphalt and other heavy oils.

Asphalt is a very heavy petroleum product which has a very limited commercial value in its natural form and which it is difficult to convert into valuable products. It is also difficult to transport due to the fact that it cannot be successfully pumped except at very high temperatures and that when transported in tank cars, it requires the use of steam to remove it from the cars.

The principal object of my invention is to provide a process by which such relatively low priced asphalt or other heavy oils and tars may be converted into more valuable products. This is accomplished by a treatment of the asphalt for the purpose of removing the lighter oils therefrom followed by a utilization of the heavier portions of the asphalt for the purpose of producing water gas.

Further objects and advantages will be made evident hereinafter.

Referring to the drawing which is for illustrative purposes only,

Fig. 1 is a cross section thru a form of apparatus adapted to carry on my process.

Fig. 2 is a section on a plane represented by the line 2-2 of Fig. 1.

Fig. 3 is a diagrammatic representation of a complete plant.

The apparatus used may conveniently consist of a special form of furnace 11, a condenser 12 and a gasometer 13 as shown in Fig. 3. The heavy oil or asphalt is delivered to the furnace thru a pipe 14. Oil is recovered from the condenser thru a pipe 15 and the fixed gases are delivered and stored in the gasometer 13 until such a time as it may be desired to utilize same.

The furnace 11 consists of a stack 21 having a tight cover 22 with an extension 23 extending upwardly and downwardly therefrom. Oil from the pipe 14 controlled, by a valve 24, is sprayed into the top of the extension 23 which extends down as shown at 25 inside the furnace forming a gas space around the outside of the portion 25. Gases

and vapors are taken away from the space 26 thru a pipe 27 and delivered to the condenser 12.

The stack 21 is initially charged with inert non-combustible material 30 which is preferably in the form of pieces of fire brick or mineral matter which will stand high temperatures without material disintegration. This mass 30 of inert material fills the stack with the exception of the space 26 and is free to pass out thru an opening 31 in the bottom of the stack, being then caught by the buckets 32 of an elevator 33 and carried upwardly inside a gas tight housing 34 and delivered thru a gas tight chute 35 into the extension 23. Air is supplied to the furnace thru tuyères 40 and this air may be subject to preliminary heating, if desired, as in blast furnace practice.

A steam pipe 41 projects into the mass 30 at the extreme bottom thereof, steam being supplied thru a perforated pipe 42 controlled by a valve 43. The bottom of the elevator is provided with a grate 50 for the purpose of separating dust and other fine material from the inert material. This dust may be removed thru slide valves 51 and 52 in an extension 53 of the elevator casing 34.

The method of operation is as follows:

The furnace is charged with the mass of material 30 which has been sprayed with asphalt thru the pipe 14 and a combustion is then set up inside the stack 21 by supplying other fuel thereto, if necessary. When the combustion is once started, it is maintained by asphalt in the combustion zone whose depth is indicated by the dimension line C between lines 60 and 61, the air from the tuyères 40 serving to maintain an incomplete combustion in this combustion zone. The space between the line 61 and a line 62 indicated by the dimension line G forms a gas producer zone, and the space between the line 60 and the top of the mass 30 marked with a dimension line D forms a distillation zone. It should be understood that the process is continuous, that asphalt sprayed thru the pipe 14 falls upon the relatively cool mass 30 in the zone G, this mass being in constant motion due to the removal of the inert material from the bottom of the stack and its delivery to the top thereof. The heavy asphalt being preferably subjected to a preliminary heating

tends to run over the individual pieces forming the mass 30 coating them in a thin film. These pieces are of sufficient size to allow gas to rise readily therethrough, this gas being 5 formed in the zones C and G. The hot gases from the zones C and G are thus in intimate contact with the thin film of asphalt on the material 30 and a distillation takes place therefrom, the lighter constituents of the 10 asphalt evaporating from the upper portion of the zone D and the heavier and less volatile portions evaporating from the lower portion of that zone, leaving material having a very high boiling point and containing large 15 masses of carbon in the form of coke or very heavy hydrocarbons. This carbon is partially consumed in the combustion zone C combining with the air supplied by the tuyères 40 to form gases of combustion 20 principally carbon dioxide. The gases of combustion at a high temperature are depended upon to assist in the distillation in the zone D. The completeness of the combustion in the zone C is controlled by controlling 25 the air admitted thru the pipe 40 to such a degree that a considerable proportion of the carbon is delivered to the zone G in the form of incandescent coke carried on more or less incandescent pieces of inert and 30 non-combustible material. Steam admitted thru the pipe 41 is allowed to rise thru this incandescent material forming a rich water gas which passes up thru the zones C and D and assists in the distillation of the material 35 in the zone D. The steam admitted thru the pipe 41 also tends to cool the extreme lower portion of the material 30 to a point slightly above the boiling point of water at which temperature it is delivered thru the opening 40 into the bottom of the elevator 33. The 45 buckets 32 pull this material over the curved grate 50, allowing broken particles of the inert material to fall therethrough as well as small particles of coke and ash. This waste material may be removed by pulling out the slide 51 and allowing the material to drop on the slide 52 after which the slide 51 may be closed and the slide 52 may be opened so that this material may be removed from the bottom 50 of the elevator 33 without admitting any great quantity of air therethrough.

The gases and vapors passing outwardly thru the pipe 27 contain certain condensable oil vapors and certain fixed gases. The oil 55 vapors are removed by the condenser 12 and delivered to pipe 15 to suitable storage, the fixed gases being delivered thru a pipe 70 to the gasometer 13. By suitable regulation of the steam and air and a suitable regulation 60 of the speed of the conveyor 33, it is possible to consume practically all of the asphalt fed thru the pipe 14. Certain portions of this asphalt form distillation products which appear finally at the pipe 15 and certain portions 65 form the fixed gases such as are pro-

duced by an ordinary gas producer. The fixed gases have a considerable commercial value and may be pumped thru pipe lines with great economy. The distillation products delivered thru the pipe 15 ordinarily 70 consist of relatively light hydrocarbon oils which also have a very considerable value. It is possible that as the asphalt passes from the zone D into the zone C that a considerable cracking action takes place. 75

I claim as my invention:

1. The process of treating carbonaceous material, said process comprising: initially mixing bitumens in a closed vertical retort with inert non-combustible material in the 80 form of pieces of mineral matter which will stand high temperatures without material disintegration, said carbonaceous and inert materials forming a porous mass, injecting steam into the lower part of said mass to generate water gas, injecting air into said mass above the point of steam injection to establish a partial combustion zone, and allowing the gases of combustion to rise to the top of said porous mass to distil volatile matter 90 from said carbonaceous material. 95

2. The process of treating carbonaceous material, said process comprising: initially mixing alphatic bitumens in a closed vertical retort with inert non-combustible material in the form of pieces of mineral matter which will stand high temperatures without material disintegration, said carbonaceous and inert materials forming a porous mass, injecting steam into the lower part of said 100 mass to generate water gas, injecting air into said mass above the point of steam injection to establish a partial combustion zone, and allowing the gases of combustion and the water gas to rise to the top of said porous 105 mass to distil volatile matter from said carbonaceous material. 110

3. A process as claimed in claim 1, characterized by continuously withdrawing part of said inert material from the bottom portion 110 of the retort.

4. A process as claimed in claim 1, characterized by the continuous removal of part of said inert material from the bottom portion 115 of the retort and its transfer to the top of said retort.

5. A process of distilling and utilizing a heavy hydrocarbon oil which comprises injecting said oil into a porous mass of inert and incombustible material, said material remaining substantially unchanged throughout the process; moving said mass downwardly to prevent bridging; injecting air into said mass to form a partial combustion zone; injecting steam into said mass below said zone to cool said incombustible material and to react with any carbon associated therewith to form water gas; and removing the products of distillation and said reaction 120 from the space above said mass. 125

6. A process of distilling and utilizing a heavy hydrocarbon oil which comprises injecting said oil into a porous mass of inert and incombustible material, said material remaining substantially unchanged throughout the process; removing portions of said mass from the bottom thereof to prevent bridging; returning the portions so removed to the top of said mass; injecting air into said mass to form a partial combustion zone; injecting steam into said mass below said zone to cool said incombustible material and to react with any carbon associated therewith to form water gas; and removing the products of distillation and said reaction from the space above said mass.

7. A process of distilling and utilizing a heavy hydrocarbon oil which comprises injecting said oil into a porous mass of inert and incombustible material, said material remaining substantially unchanged throughout the process; consisting of pieces of an inert and incombustible substance; moving said mass downwardly to prevent bridging; injecting air into said mass to form a partial combustion zone; injecting steam into said mass below said zone to cool said incombustible material and to react with any carbon associated therewith to form water gas; and removing the products of distillation and said reaction from the space above said mass.

8. A process as in claim 1 in which the car-

bonaceous material is in the form of a heavy liquid.

9. A process as in claim 2 in which the carbonaceous material is in the form of a heavy liquid.

10. The process of treating asphalt to produce fixed gas and light oil which comprises: initially mixing asphalt with broken pieces of refractory material in a closed vertical retort to form a porous mass; injecting steam into the lower part of said mass to generate water gas; injecting air into said mass above the point of steam injection to establish a partial combustion and cracking zone; allowing the products formed in said zone to rise to the top of said porous mass and to distill volatile material from the asphalt; separating the liquid and gaseous portions of the distillate; and continuously supplying the retort with additional asphalt.

11. A process as claimed in claim 8, characterized by the continuous removal of part of said refractory broken brick from the bottom portion of the retort and its transfer to the top of said retort.

12. A process as claimed in claim 8, characterized by the continuous supply to the top of the retort of asphalt in melted condition.

In testimony whereof, I have hereunto set my hand at San Francisco, California, this 19th day of August, 1920.

DANIEL PYZEL.
